UNITED STATES PATENT OFFICE.

EBEN C. SPEIDEN, OF NIAGARA FALLS, NEW YORK.

VALVE-OPERATING MECHANISM FOR LAVATORIES.

1,176,784.

Specification of Letters Patent. Patented Mar. 28, 1916.

Application filed May 10, 1915. Serial No. 27,213.

To all whom it may concern:

Be it known that I, EBEN C. SPEIDEN, a citizen of the United States, residing at Niagara Falls, in the county of Niagara 5 and State of New York, have invented certain new and useful Improvements in Valve-operating Mechanisms for Lavatories, of which the following is a specification.

This invention relates to valve-operating 10 mechanism for lavatories, and especially to such mechanism designed to be operated by the foot. Various devices of this general nature have been heretofore proposed, some controlled by the knees and some by the feet 15 of the operator, but in none of these is it possible to secure the adjustment and combination of action accomplished by the use of the present invention.

Several embodiments of the invention are 20 illustrated in the accompanying drawings, in which:—

Figure 1 is a front view of a preferred form of device; Fig. 2 illustrates the invention in perspective as designed for attachment to the ordinary basin; and Figs. 3 to 25 6 show perspective views of several possible forms of compound-movement bearings for the pedal.

As illustrated in Fig. 1, the basin 1 has 30 the usual supply-pipes 2, 3 for hot and cold water, respectively, leading to a suitable mixing-chamber 4. In the pipes 2 and 3, there are valves 5, 6, preferably of the rotary type by which the supply of water may 35 be regulated. The valves 5, 6 are so arranged in their seats that they will assume their open positions only when turned in a single direction, and will not be opened by any movement in the opposite direction past 40 the normal closed position, as will be presently understood. From the mixing-chamber 4 a pipe 7 leads upward to the bowl 1. The valves 5, 6 are controlled by short links 8, 9, respectively, any movement of 45 the latter serving to turn its valve in its seat.

Beneath the basin 1, and conveniently located on the floor 10, there is fixed a pedestal 11 pivotally supporting some distance from 50 the floor, by means of suitable lateral trunnions 12, a cradle 13. The cradle carries within it a relatively freely-revolvable rock-shaft 14, secured at its inner end 15 to an operating cross-bar 16. The outer end of 55 the rock-shaft 14 is provided with an elongated pedal 17, the ends 18, 19 of which are

stamped or otherwise marked with the words "Hot" and "Cold," and the center may be marked "Warm." The shaft 14 can be readily rocked within its cradle 13 by 60 pressing with the foot on either end of the pedal 17, and may be tilted on the trunnions 12, independently of its rocking movement, by pressing upon the central portion of the pedal. 65

Pivotedly attached to the ends 20, 21 of the cross-bar 16 are two levers 22, 23 connected at their upper ends to the links 8, 9 by pivots 24, 25. Thus, any movement of the rock-shaft 14 in either of its two directions of oscillation will turn the valves 5, 6 in their seats. If the valves 5, 6 are not automatically closed upon release of the rock-shaft, suitable springs or weights may be attached to some convenient portion of 70 the mechanism in any well-known manner for accomplishing this automatic return of the parts to their inoperating positions. 75

According to the slight modification illustrated in Fig. 2, wherein the invention is 80 adapted to be attached to a basin having ordinary exposed faucets, the cross-bar 16 is pivotally connected at its ends 20, 21 to push-links 30, 31 having upwardly extending guide-pins 32, 33. These pins pass 85 freely through eyes formed in the lower ends of elongated levers 22', 23', fulcrumed midway their length as at 34 to some fixture, e. g. to the sides of the basin 1, as shown. At the base of the guide-pins 32, 33 the links 30, 31 are formed or provided with enlarged or shoulder portions 39, 40 upon which the lower ends of the levers 22' and 23' respectively rest. The upper ends of the levers 22', 23' are pivoted to links 8', 9', operatively attached to the valve-handles 35, 36 of the faucets 37, 38 so that any outward movement of the links 8', 9' will serve to open the valves, as by turning the same. The faucets are preferably of the well-known self-closing type, so that when the levers 22', 23' are released the parts will 90 reassume their inoperative positions. 95

In use, as will be apparent, pressure on the right end 19 of the pedal 17 will cause 100 the shaft 14 to rock in its elongated bearing or cradle 13, causing the cross-bar 16 to tilt to raise its left end 20 and to lower its right end 21. Such movement of the parts in the form shown in Fig. 1 will cause, through 105 110 the levers 22, 23, the valve-operating links 8, 9 to be thrown up and down, respectively,

The consequent movement of the valve 6 beyond its normal closed position does not, as before mentioned, open its water passage, but the clockwise movement of the other 5 valve 5 in its seat causes its port to register with the openings in the pipe 2, and hot water will run into the bowl 1. If pressure is applied with the foot to the left side 18 of the pedal 17, a reversal of the above-described 10 movements will occur, the valve 5 this time remaining closed, and the valve 6 will be turned to allow passage of cold water to the bowl 1. Obviously, the parts may be slightly changed so that cold water will 15 be supplied when the right-hand side of the pedal 17 is depressed, and the hot-water valve opened when the left-hand portion of the pedal is depressed. Also, as will be apparent, the valves 5, 6 may be opened by 20 turning them in the directions opposite to those stated in the foregoing description.

According to the embodiment illustrated in Fig. 2, when the right-hand end 19 of the pedal 17 is depressed, and the cross-bar 25 16 tilted in the manner above described, the link 30 will be thrust upward while the link 31 will move downward. The shoulder 39 engaging the lower end of the lever 22' will rock the latter about its fulcrum 34, 30 the resulting pull outward on the link 8 will turn the handle 35 of the faucet 37, and thus permit cold water to flow into the basin. The operating lever 23' remains undisturbed in the meantime, as during the 35 fall of the link 31 the pin 33 rides freely downward through the eye in the lever 23'. Likewise, when the left side 18 of the pedal is depressed, the link 31, lever 23' and link 9' are moved to effect the opening of faucet 40 38 to supply hot water to the bowl. Here, as before, the parts might be slightly shifted so that pressure on the right-hand side of the pedal will open the hot-water valve and depression of the left-hand end of the 45 pedal will cause the opening of the cold-water valve. Also, the levers 22', 23' need not cross, but may be arranged to extend upward from their respective links 30, 31 to the valve on the same side of the basin 50 therewith.

In both of the forms of the invention above described, pressure applied along the center of the pedal 17 will cause the rock-shaft 14 to be tilted in a vertical plane about 55 the trunnions 12. Thereupon, the entire bar 16 will be raised, both connecting levers 22, 23 or 22', 23' will be thrust upward, and both the hot and cold-water valves opened. By releasing one end or the other of the pedal 60 to permit that end to rise to a greater or less degree, it is possible to quite effectively control the temperature of the water in the basin.

If found desirable, an enameled or nickel-plated casing 41 may be fitted about the

bearing, suitable apertures or cut-away portions 42, 43 and 44 being provided to accommodate the protruding parts. Also, the entire mechanism can be shifted to be operated in planes at 90° from the planes in which 70 the parts are shown in the drawings, so that the shaft or operating-levers will be substantially vertical, and the reach-rods connecting the levers to the valves will run horizontally.

Obviously, the bearing of the pedal 17 may be somewhat widely varied in construction, without departing from the spirit of the invention, and several other forms are 75 illustrated in Figs. 3 to 6.

As shown in Fig. 3, the fulcrum 12³ of the cradle 13³ is located in the rear, and the cross-bar 16³ is fixed to the central portion of the shaft 14³. The valves would in such case be operated by the downward pull 85 given to the links 30³, 31³ by depression of the pedal 17³.

According to the form illustrated in Fig. 4, two operating-bars A and B, one for each of the links 30⁴ and 31⁴, are provided, these 90 bars being mounted upon fulcrums 12^a and 12^b. The front or outer ends of the bars A, B are connected by a cross-bar 17⁴, so that both bars may be tilted simultaneously by depression of the pedal-bar 17⁴, with one 95 foot of the operator. However, the connections between the pedal 17⁴ and the bars A, B are of such nature that depression of one of the bars A, B may be effected without movement of the other. This may be 100 accomplished by providing ball-and-socket joints C, D, as shown, or by any other suitable means, not necessary to describe. The modification shown in Fig. 5 differs from that shown in Fig. 4 only in that, as in Fig. 105 3, the fulcrums of the operating elements are located at or near their inner ends 14^a, 14^b, while the pull-rods 30⁵ and 31⁵ are carried intermediate the lengths of the bars.

In Fig. 6 there is illustrated a pedal 17⁶ 110 extending across and supported upon a single-point bearing 12⁶, of any appropriate form. The pedal in such case may be a plane wooden or metal plate, and it may be provided on its under side with a socket 115 adapted to receive a ball or other bearing carried upon the top of a suitable pedestal 11⁶. The links 30⁶ and 31⁶ are attached to the inner end of the pedal 17⁶, as in Figs. 1, 2, etc. In the use of a device of this kind, the foot of the operator is placed on top of the pedal 17⁶, the toe on the inner portion somewhat adjacent the links 30⁶ and 31⁶, and the heel on the outer portion, so that the arch of the foot rests above or 120 nearly above the bearing 12⁶. By bending the foot laterally to the left or right, the rods 30⁶, 31⁶ may be made to move up and down to open either of the water-valves, 125 independently of the other; and by depress- 130

ing the outer end of the pedal 17° with the heel, or the inner end with the toe, if the links 30°, 31° operate the valves by pull, both valves can be opened simultaneously.

5 By tilting the pedal 17° at various angles about its bearing 12°, the temperature of the water admitted to the bowl may be quite effectively regulated.

Foot-operated valves for lavatories are 10 of course old in the art, but I believe that I am the first to provide mechanism whereby the movement of a single pedal serves to open one of the valves quite independently of the other, or to open both valves simultaneously, at the desire of the operator.

I claim:—

1. Lavatory apparatus, comprising hot and cold water valves having operating connections, rocking means for actuating one or the other or both of said connections, 20 and a single pedal for rocking said rocking means.

2. Lavatory apparatus, comprising hot and cold water valves, a rock-shaft, an operating bar connected to said valves, said 25 bar being mounted on said rock-shaft to

oscillate therewith transversely of the axis of the rock-shaft and thereby actuate one or the other of said valves, and means for rocking said rock-shaft and for independently 30 tilting it to actuate said valve simultaneously.

3. Lavatory apparatus, comprising hot and cold water valves, a rock-shaft connected with said valves, means for rocking said 35 rock-shaft to thereby actuate one or the other of said valves, and means for tilting said rock-shaft to thereby actuate said valves simultaneously.

4. Lavatory apparatus, comprising hot 40 and cold water valves, a rock-shaft connected with said valves and oscillative about axes at right-angles to each other to actuate one or the other or both of said valves, respectively, and a single pedal for turning 45 said rock-shaft about either axis.

In testimony whereof I affix my signature in presence of two witnesses.

EBEN C. SPEIDEN.
